Leon Cammen
INVENTOR.

UNITED STATES PATENT OFFICE.

LEON CAMMEN, OF NEW YORK, N. Y.

MOLD FOR CENTRIFUGAL CASTING.

Application filed March 30, 1926. Serial No. 98,546.

The present invention refers to a machine for casting centrifugally such objects as split tubes, bars, ingots, gears and the like, and generally objects in the casting of which is used a mold of which the inner surface is not smooth but equipped with projections. The invention set forth here is a modification and development of the one covered by U. S. Patent No. 1,490,589.

10 In the illustrations,

Fig 1 is a section through the mold in a plane normal to the axis of rotation; as at A—B, Fig. 2;

15 Fig. 2 is a section through a plane comprising the axis of rotation.

Fig. 3 is an end view of a gate which may be set at 21, Fig. 2.

The mold shown in my U. S. Patent No. 1,490,589 above referred to consists essentially of two parts disposed along the axis of rotation, one smooth, against which the metal of the casting is fed, and the other equipped with projections of a shape suitable for the desired casting. If metal were 20 fed directly against the part of the mold equipped with the projections while the mold is spinning, it would be struck by the projection, scattered, and ultimately cause "cold shuts" in the casting. If it is fed 25 against the smooth part, it acquires the speed of the mold before coming into contact with the projections, and hence there is no blow and no tendency for the metal to scatter. On the other hand, however, the metal 30 has to be all supplied from one end, and distributed from end to end of the mold by the pressure produced by centrifugal force which naturally limits the length of the objects that can be cast. This is particularly 35 so in the case of metals which freeze very rapidly, or which have to be cast at temperatures very close to their temperature of solidification. The present invention eliminates these limitations.

40 The mold consists here of two parts, disposed along the axis of rotation, mold proper 1 and distributor 14 (Fig. 2). The mold proper may be equipped with projections, such as 6 (Fig. 1). The mold is also 45 equipped with heads or gates 12 and 13 which make the metal build up in the mold to the desired thickness rather than fly off in the direction parallel to the axis of rotation. The distributor part of the mold, 14,

may be equipped with such a head or gate, 55 15, only at one end, the pouring end.

The mold proper and the distributor are both made to rotate, preferably at the same speed, and certainly in the same direction. Molten metal may be supplied to the distributor, as by spout 17 which is the method 60 commonly used in centrifugal casting. The liquid metal coming from the spout 17 is picked up by the distributor 14 and set into rotation; it is then subject to the action of 65 centrifugal force, and forced to spread lengthwise (cp. Transactions, American Society of Mechanical Engineers, vol. 44, 1922, pp. 284-5). In Fig. 2 the gate 15 does not permit the metal to flow beyond that point 70 to the right, but it is free to discharge over the edge to the left. In doing so, the metal falls onto the mold proper 1 and fills the spaces between the projections 6. There is no blow however of the projections 6 against 75 the metal, as there would have been if the metal were discharging from the spout 17 directly into the mold 1, because as far as the relation of flowing metal and projections 80 6 is concerned, both the distributor and the mold, running at the same or approximately the same speed, may be considered as—relatively—standing still. The means for rotating the mold proper and distributor 14 are not shown, as they are matter of common 85 engineering knowledge.

The mold proper 1 and distributor 14, if desired, may be given a relative displacement longitudinally, by shifting endwise either the mold proper or the distributor 90 while the metal is being supplied to the latter. There are many well known ways of doing it, and any engineer skilled in his art would know how to accomplish it.

The distributor 14 may have its inner 95 surface cylindrical, conical, or cylindrical in one part, and conical in another part, the selection of any particular arrangement being merely a matter of design.

In my U. S. Patent No. 1,553,136, I have 100 shown partition lugs equipped with shoulders to keep the casting from falling away from the mold to a greater extent than is desired, and for other purposes set forth in the above patent. A lug similar to those 105 shown in the patent here referred to is shown in Fig. 1 at 18. This lug has its upper face 19 shaped as part of an arc

of a circle drawn about the axis of rotation. There is no objection to this with the usual bottle-neck mold, such as shown in my Patent No. 1,490,589, because there the metal 5 of the casting never comes in contact with the upper face of the lug. With a mold having a rotating distributor such as 14 in the present invention, part of the metal 10 discharges over the lug. It is therefore desirable to make the upper face of the lug of such a shape that the metal would have as little as possible tendency to stay on it, and that on the contrary it would discharge 15 from it with as little splashing as possible. This can be done in several ways, as by giving the top of the lug a face with a slant, as at 11, or a gable, as at 24, or any combination or known modification of these two 20 roof types. It is therefore proper to describe the upper face of the lugs as "roof-shaped", this term being here applied to the above two types of roof, their known combinations and modifications. Thus, e. g., the gable 24 might easily be modified to 25 a parabolic section without changing the intent and purpose of the invention.

Where there is no relative motion along the axis of rotation between the distributor 14 and mold proper 1, the former may be 30 equipped at 21 with a head or gate, such as shown in Fig. 3. This gate has pieces 23 projecting into the interior of the distributor at the discharging end. The size, number and location of these pieces 23 is 35 so selected with respect to the lugs 6 in the mold proper as to prevent any metal from discharging over the lugs, but to provide for a free discharge of the metal into the spaces between the lugs. The value of this arrangement would be lost where the distributor 40 does not run at the same speed as the mold proper. In fact, where such an arrangement is used, the distributor might be attached solidly to the mold proper, and 45 only one of them directly driven. An equivalent arrangement might be adopted by providing the end 21 of the distributor with a gate similar to 13, and then cutting in the distributor near the gate just referred to, slots.

Where the distributor has no longitudinal displacement, it may be well to equip the mold proper with a ring of fireproof material, such a clay or cement, in the 55 places where the metal coming from the distributor strikes the mold, to prevent washing the metal of the mold away.

As regards the relative rotational speed 60 of the mold proper and the distributor, there is no advantage whatsoever in having the speeds of the two, in revolutions per unit of time, differ. On the other hand, apart from possible splashing of the metal where it hits the top faces of the lugs, there 65 is no special disadvantage in having them

run at slightly different speeds. A great difference in speed would be productive of splashing and scattering of the metal.

No reference to the matter of relative rotational speeds of 1 and 14 is made in the 70 claims as this factor does not enter into the design of the mold, but may be controlled by the motor drive.

I claim:

1. A mold for centrifugal casting consisting of two parts disposed along the axis of rotation, of which parts the one against which the metal of the casting is fed, has a smooth internal surface, and the other part has projections of a shape suitable for the 80 desired casting, and the former of the two projects into the latter and is connected thereto.

2. A mold for centrifugal casting consisting of two parts disposed along the axis of 85 rotation, of which parts the one against which the metal of the casting is fed, has a smooth internal surface of cylindrical shape, and the other part has projections of a shape suitable for the desired casting, the first 90 of said two parts above referred to projecting into the second one, and being connected thereto.

3. A mold for centrifugal casting consisting of two parts disposed along the axis of 95 rotation, of which parts the one against which the metal of the casting is fed has a smooth internal surface of the shape of a truncated cone contracting towards the pouring end, and the other part has projections 100 of a shape suitable for the desired casting, the first of said two parts above referred to projecting into the second one, and being connected thereto.

4. A mold for centrifugal casting consisting of two parts disposed along the axis of rotation, of which parts the one against which the metal of the casting is fed has a smooth internal surface of a shape which is a combination of cylindrical and truncated 110 cone with the latter contracting towards the pouring end, and the other part has projections of a shape suitable for the desired casting, the first of said two parts above referred to projecting into the second one and 115 being connected thereto.

5. A mold for centrifugal casting consisting of two parts disposed along the axis of rotation, of which parts the one against which the metal of the casting is fed has a 120 smooth internal surface, and the other part has projections of a shape suitable for the desired casting, the former of the two parts projecting into the latter, and both being provided with means for imparting to them 125 a rotary motion.

6. A mold for centrifugal casting consisting of two parts disposed along the axis of rotation, of which parts the one against which the metal of the casting is fed has a 130

smooth internal surface of cylindrical shape, and the other part has projections of a shape suitable for the desired casting, the first of said two parts above referred to projecting into the second one and both being provided with means for imparting to them a rotary motion.

7. A mold for centrifugal casting consisting of two parts disposed along the axis of rotation, of which parts the one against which the metal of the casting is fed has a smooth internal surface of the shape of a truncated cone contracting towards the pouring end, and the other part has projections of a shape suitable for the desired casting, the first of said two parts above referred to projecting into the second one and both being provided with means for imparting to them a rotary motion.

8. A mold for centrifugal casting consisting of two parts disposed along the axis of rotation, of which parts the one against which the metal of the casting is fed has a smooth internal surface of a shape which is a combination of cylindrical and truncated cone with the latter contracting towards the pouring end, and the other part has projections of a shape suitable for the desired casting, the first of said two parts above re-

ferred to projecting into the second one and both being provided with means for imparting to them a rotary motion.

9. A mold for centrifugal casting consisting of two parts disposed along the axis of rotation, of which parts the one against which the metal of the casting is fed has a smooth internal surface, and the other part has projections of a shape suitable for the desired casting, the former of the two projecting into the latter, being connected thereto and being provided at the discharge end with means to direct the flow of liquid metal therefrom into the spaces between the projections above referred to and to keep said flow of liquid metal away from said projections.

10. A mold for centrifugal casting consisting of two parts disposed along the axis of rotation, of which parts the one against which the metal of the casting is fed, has a smooth internal surface, and the other part has projections of a shape suitable for the desired casting and roof-shaped tops, the first of said two parts above referred to projecting into the second one.

Signed in New York, in the county and State of New York, March 26, A. D. 1926.
